ADJUSTABLE AWNING SUPPORT

Max Lipkowitz, Brooklyn, N. Y.

Application December 19, 1931
Serial No. 582,126

3 Claims. (Cl. 156—44)

This invention relates to awning supports, and has for an object the provision of an awning supporting arm, which may be adjusted to vary the distance of the outer end of the arm from its support and the height of the end of the said arm above the sidewalk, with a corresponding change in the relation of the awning supported upon the said arm.

The invention has in view an awning support adapted to be affixed to the front of buildings for supporting an awning in position to give the required shade to the windows or store front, and for this purpose the said arm is provided with means for producing a step-by-step adjustment 15 of the elevation of the awning support, as well as small increments of adjustment, without altering or changing the attachment thereof to the building.

Another object of the invention is the provision of an awning arm constructed to fold to an upright, collapsed position against the wall of the building, so that it takes up as little room as possible when in such position.

With these and other objects in view, the invention resides in the novel features of construction and arrangement of parts which will be more fully described and claimed hereinafter.

The invention is shown in the accompanying drawing in which

30 Figure 1 is a side elevation, showing the awning side arm in extended position, and in dot-and-dash outline the said arm in collapsed or folded position;

Fig. 2 is a top plan view of the awning side arm;

Fig. 3 is a cross-sectional view through one of the brackets for attaching the arm to a building, and showing a portion of the means for adjusting the arm;

40 Fig. 4 is a vertical sectional view on the line 4—4 of Fig. 3.

In the drawing illustrating the preferred embodiment of the invention, a single awning side arm 10 is shown, it being understood that one such arm is applied to the building at each side of a window or store front. A bar 11 is arranged between the outer ends of said side arms, to which bar the outer end of the awning 12 is secured.

The arm 10 comprises a lever arm 13 pivotally mounted at its lower end to a bracket 14, which bracket is adapted to be secured to the face of a building, indicated in the drawing by the line 15, by any desired means, such as screws 16. The opposite end of the lever arm 13 is pivoted to an arm 17, and between its ends to an arm 18 at the point

19. The lever arm 13 is preferably a flat bar, while each of the arms 17 and 18 consists of a pair of bars of channel formation, between which the arm 13 is pivoted, as hereinbefore described. The inner end of the arm 18 is pivoted to the outer end of an adjustable lever arm 20, the opposite end of which lever arm is pivotally connected between the lugs of a slide 21. The said slide 21 is movable on a bar 22 of a bracket 23 and is adapted to be secured in various positions thereon, to provide a step-by-step adjustment of the point of attachment of the said slide on said bar, with a corresponding change in elevation of the outer end of the lever 10. The bracket 23 is adapted to be secured to the wall of a building in vertical alignment with the bracket 14.

The arm 18, at its outer end, is pivoted to the inner end of an outwardly-extending arm 24, and between its ends the arm 24 is pivotally connected at 25 to the outer end of the arm 17. This construction provides a pair of levers which may be folded to an upright, collapsed condition, and when in extended position provides a means of support for the awning, which may be adjusted to change the height of the awning above the sidewalk and the distance of the outer edge of the awning from the building.

To provide both small increments of adjustment and step-by-step adjustments of the said distances, the lever arm 20 is made adjustable 85 in length, and the slide 21, to which the said arm 20 is pivotally connected, is adapted to be secured at different positions on the bar 22, as hereinbefore described. As shown in the drawing, the slide 21 is provided with a set screw 26, 90 which is adapted to engage any one of the depressions 27 in the bar 22, to hold the slide in fixed position thereon. The bar 22 may be of any desired length and the depressions 27 spaced along the bar to provide the step-by-step adjustment that is desired. The lever arm 20 may be lengthened to provide either very small increments of adjustment or a relatively large degree of adjustment. As shown in the drawing, the length of this lever arm may be changed 100 by rotating the sleeve 28 to produce a spreading apart of the threaded bars 29 and 30, one of said bars being provided with a right-hand thread and the other with a left-hand thread, which engage the correspondingly threaded bore of the sleeve 28. It will be understood, of course, that by turning the sleeve 28 a fraction of a turn, the degree of adjustment imparted to the outer end of the arm 24 is relatively small, and turning the sleeve a number of turns will impart 110

a correspondingly greater adjustment both as to the distance of the outer end of the arm from the building and the height of the outer end from the sidewalk.

5 In order that the side arm 10 may be arranged in compact formation when in collapsed condition, the ends of the arms 13, 18 and 24 are each curved so that when the support is in vertical position, these arms will come together in substantially parallel alignment. For this purpose also the end 32 of the lever arm 20 is offset, so that its pivotal connection with the lever 18 will permit the said bars to be arranged in substantially parallel relationship when in collapsed condition.

15 The awning 12 is wound on a spring roll 31 attached at its ends to the building above the awning support, the outer end of the awning being affixed to the bar 12 connected between the 20 ends of the arms 24, as hereinbefore described. By means of the spring roll any slack in the awning will be taken up, and when the awning arm is arranged in collapsed condition substantially the full length of the awning will be rolled 25 up on the said roll.

What is claimed is:

1. An awning support comprising in combination with a vertically swingable side arm structure, including a pair of relatively swingable 30 lever arms, one of which arms has a fixed fulcrumed connection with a support; means for supporting the other lever arm for vertical adjustment, said means including a bracket having upper and lower portions for attachment to said support, one of said portions having an opening therein, a bar of rectangular shape in cross section connected with the other of said portions and with its free end disposed in the opening of said first mentioned portion, a member having a rectangular opening for receiving said bar and on which bar the said member is vertically 35 slideable, said member having forwardly extending furcations, a longitudinally extensible link having one end disposed between and pivotally connected with said furcations and a pivotal con-

nnection between the other end of said link and said other lever arm to permit of vertical swinging movement, said bar having a series of depressions and said member having means for selective engagement with said depressions for securing the member and link in vertically adjusted positions.

2. An awning support comprising in combination with a vertically swingable side arm structure, including a pair of relatively swingable lever arms, one of which arms has a fixed fulcrumed connection with a support; means for supporting the other lever arm for vertical adjustment, said means including a bracket having upper and lower portions for attachment to said support, a bar of rectangular shape in cross section bridging the said upper and lower attaching portions, a member having a rectangular opening for receiving said bar and on which bar the said member is vertically slideable, said member having forwardly extending furcations, the other lever arm being pivotally connected at one end with said furcations for vertical swinging movement, and means on the said member engageable with the said bar for selectively securing the member and lever in vertically adjusted positions.

3. An awning support comprising in combination with a vertically swingable arm structure, including a pair of relatively swingable lever 105 arms, one of which arms has a fixed, fulcrumed connection; means for supporting the other lever arm for vertical adjustment, said means comprising a vertically disposed non-circular guide element attached to the wall front in spaced 110 parallel relation thereto, a non-rotary slide mounted on and surrounding said guide element for vertical adjustment and with which member said other lever arm has a fulcrumed connection and means on the guide element engageable 115 with the slide member for selectively locking the slide member in one of a number of vertically adjusted positions.
